(57) **CLAIM**

The ornamental design for a white noise and sleep aid device in combination with a plush toy, as shown and described.

DESCRIPTION

FIG. 1 is a front view of white noise and sleep aid device in combination with a plush toy, illustrating the present design;

FIG. 2 is a rear view thereof;

FIG. 3 is a side view thereof;

FIG. 4 is a top plan top down view thereof; and,

FIG. 5 is a bottom view thereof.

The broken lines show portions of the white noise and sleep aid device in combination with a plush toy that form no part of the claimed design.

1 Claim, 5 Drawing Sheets
